UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Original application filed September 27, 1922, Serial No. 590,756. Divided and this application filed January 7, 1925. Serial No. 972.

The present invention relates to sound-deadening casings for typewriting machines.

A casing of this character has an opening in the front thereof, through which the keyboard extension of the machine may project, for access by the operator to the keys thereof. The casing, at its base, is ordinarily of a width conformable to the width of the main frame of the machine; allowance being made for easy placement and removal of the machine; but, above the base, is flared or extended laterally outward to provide space in the upper part thereof, for movement of the typewriter-carriage in letter-feed and return directions; and the upper part of the casing is slotted horizontally and longitudinally thereof, for projection therethrough, and for movement therealong, of the operating levers on the typewriter-carriage.

The casing is usually made in two sections, to wit, a body-section, provided with a suitable base-piece, and a cover-section, hinged thereto; the cover being opened for placement and removal of the machine. The opening in the front wall of the casing for the keyboard extension may extend to the top of the casing-body; or may not extend to the top of the casing-body, in which latter event the machine may be inserted into the casing, in tilted position, and the keyboard extension passed forward through the opening in the front wall thereof. A window in the top of the casing has been provided for observation of the printing on the platen. The shell-sections of the casing, either as die-castings or as sheet-metal stampings, have been provided with lining-sheets of sound-deadening material, such as felt; and the joints thereof, at the openings or slots, through which project the keyboard and the operating levers of the machine, have been equipped with cushions or edgings, which close the same against the emission of sound when the machine is in place; without, however, interfering with placement or removal of the machine, or with movement of the carriage and operating levers thereon.

The invention, as to certain features thereof, has special reference to casings made of

sheet-metal, and to casings in which the opening for the keyboard extension of the machine extends to the top of the casing-body, to permit placement of the machine without insertion of the keyboard extension into the body thereof.

A feature of the invention is the provision of novel and efficient means for closing the joints at the sides of the machine between the keyboard extension and casing; and above the keyboard extension, between the front wall of the machine-frame and the casing; such means being torsionally resilient and flexible, so that there may be maintained a pressure of the upper portions thereof, rearward against the front of the machine, and of the lower portions thereof laterally against the keyboard extension of the machine, to close, throughout their lengths, the joints between the several parts of the machine and the casing; while permitting proper flexing thereof for insertion and removal of the machine.

Another feature of the invention is the provision of a removable plate, adapted, when in place, to close the upper portion of the opening in the front wall of the casing over the keyboard extension, and to seat, in a novel and effective manner, the cushion which forms the lower wall of the slot, along which the operating levers on the carriage move; this removable plate with the cushion and cushion-seat, and suitably equipped with sound-deadening material to close the joint between the casing and the front of the machine, being securely and quickly attachable, as a whole, to the casing front wall at the upper edge thereof.

A further feature of the invention is the provision of a shade on the casing, to intercept light-rays which would otherwise be objectionably reflected from the window-pane to the eyes of the operator; such shade being securely flexible to the shell of the casing, and, in the preferred form thereof, being a strip of rail or sheet-material, projecting marginally upward from the edge of the window, and serving as a frame for the window-pane.

Still another feature of the invention is a casing, and the method of making the

same, wherein the shells, forming the body-portion and the cover, are each of unitary, seamless structure, drawn into shape by suitable dies or presses, while in heated condition.

5 This application is a division of my co-pending application, Serial No. 590,756, filed September 27, 1922 (now Patent No. 1,570,309, dated January 19, 1926).

10 Other features and advantages will hereinafter appear.

In the accompanying drawings,

15 Figure 1 is a view, in front elevation, partly in cross-section, of the casing; the keyboard extension of a typewriting machine being shown protruding through the front wall of the casing.

Figure 2 is a view, in cross-sectional side elevation, taken on the line 2—2 of Figure 1.

20 Figure 3 is a top plan view of the casing, the cover being broken away to show the interior of the casing-body.

Figure 4 is a rear view of a piece forming, when in place, the upper portion of the 25 front wall of the casing.

30 Figure 5 is a view, in longitudinal cross-section, taken on the line 5—5 of Figure 2, showing the means for attaching and locking the front piece of Figure 4 to the main body-portion of the casing.

35 Figure 6 is a detail view, taken in cross-section on the line 6—6 of Figure 1, through the sound-deadening device at the side edge of the opening in the front wall of the casing; one of the front posts of the typewriting machine, and the position of the device when the machine is in place in the casing, being shown in dotted lines.

40 The casing is in two principal parts, to wit, a body-portion 10 and a cover 11; the cover being hinged at 12 at the rear thereof to the body-portion. Both the casing-body and cover are shown as of sheet-material, preferably aluminum. The rear, front, and 45 side walls of the casing-body are lined with sound-deadening material 13. The front wall of the casing is cut away, as at 14, so that the keyboard extension 15 of the typewriting machine 16 indicated in dotted lines 50 may protrude therethrough.

55 For securing the lining 13 to the sheeting 10 of the casing, the latter has, staked therein, near its upper and lower edges, bosses or bushings 17, which pass through openings in the lining, and which are threaded to receive screws 18, which pass through retaining straps 19 laid longitudinally of the inner face of the lining, to hold the straps to the bushings 17. At its lower edges the 60 sheeting 10 has a reinforcing bead 20 formed peripherally thereon; and, from the bead 20, is turned inward to form a horizontal peripheral flange 21 upon which the lower edge of the lining 13 is set. At the front 65 of the casing-body the lining 13 terminates

70 with the sheeting 10 at the sides of the opening 14 for the keyboard extension. Below the keyboard extension, the sheeting 10 is continued, from side to side of the casing, as a slightly offset strip 10^a (see Figure 2). The piece 10^a is lined with a sound-deadening strip 23 held thereto by a strap 24, which is secured by screws 18^a to bushings 17^a staked or riveted in the sheet-metal. The lining-strip 23, like the lining 13, is set 75 upon the peripheral flange 21 of the casing-body. The upper edge of the lining-strip 23 is extended, as at 23^a, as a resilient tongue to engage and press against a rod 26 on the machine when the latter is in 80 place.

85 As shown in Figure 1, the casing is flared laterally upward and outward on the lines 30, to provide room in the top thereof for movement of the platen-carriage in letter-feed and return directions. The flaring side walls 30 terminate, at their upper ends, in horizontal overhangs 31, the ends of which are turned upward, to form flanges 32. The side lining-pieces 13 extend upward from 90 the flange 21 at the foot of the casing-body, along the flaring walls 30, and thence, with reduced thickness on the left-hand overhang across the overhangs, to the flanges 32, where they are again turned up to the height of 95 the flanges 32. Near their lower edges, and at their upper edges, the side lining-pieces 13 are secured to the sheeting of the casing-body by straps 19, in the manner hereinbefore described. Where the left side piece 100 13 is bent from a lateral flare to the horizontal overhang, it is held by a strap 33, carried on fingers 34, secured to the front and rear walls of the casing-body by two 105 of the screws 18, which assist in holding the front and rear upper straps 19. It will be noted (see Figure 1) that the strap 33 is bent longitudinally, as shown at 35, to the desired bend of the lining-piece, from an 110 upward incline to a horizontal.

115 When the machine is in the position in the casing determined by the location of its feet in guards 60, the front corner-posts 70 of the machine, as shown in Figure 3, abut the front wall of the casing at the side edges of the opening in the latter for the keyboard extension. For providing a sound-deadening joint on the lines of contact of the front posts of the machine with the front wall of the casing, and where the keyboard extends through the latter, cushions 71 (see Figure 6) are provided. These 120 cushions, which extend vertically along the side walls 72 of the opening in the casing, each comprise a rubber tubing 73, held in the fold of a strip of felt 74; the ends of the felt being brought together and held to the casing by vertical straps 75, which, like the straps 19, are secured to bushings 76, staked or riveted to the sheeting 10 of the 125 130

casing, by screws 77, which pass through the straps, through the edges of the felt 74, and thread into the bushings. As shown in Figure 6, the cushions 71 are flexibly held 5 to the casing, so as to be movable by the posts 70 of the machine from a normal, full-line, Figure 6 position to the dotted-line, Figure 6 position. In the latter position, the cushions, by reason of their spring-setting, 10 bear against the posts of the machine and effectually close the joint between the machine and the casing. The flexible mounting of the cushions permits the same to be swung rearward by the side plates of 15 the keyboard extension, as the machine is set into the casing or removed therefrom; and, when the machine is in place, the dotted-line, Figure 6, setting of the upper portions of the cushions, effected by the 20 posts of the machine, will, by reason of the rubber tubing 73, cause the lower portions of the cushions to bear closely against the keyboard extension; to seal the joints alongside the latter, as well as the joints between 25 the posts and the casing above the keyboard extension.

To permit the machine to be readily placed within, and removed from, the casing, the front wall of the latter, above the 30 position of the keyboard extension, is provided with a removable member (see Figures 2, 4 and 5). This removable member comprises a plate 78, adapted to extend from side to side of the wider upper portion 35 of the casing. The plate 78 carries a strip 79 of sound-deadening material. As shown in Figure 4, the strip 79 extends along only that portion of the plate 78 which overlies the opening in the front wall of 40 the casing; and, when the machine is in place, this strip 79 abuts the upper portion of the front of the machine-frame, closing the casing at this point against emission of sound. The plate 78 also carries the cushion 80, which forms the lower wall of the 45 slot in the casing, along which the operating levers on the carriage of the machine move in the letter-feed and return movements of the latter. These levers are the line-space lever 81, carriage-return arm 82 and carriage-release lever 83. The cushion 80 comprises a rubber tubing 84, held in the fold of a strip of felt 85; the edges of the felt being brought together, at 86, between the plate 78 and the lining strip 79. A strap 87 extends along the inner face of the lining-strip 79, and along the plate 78 beyond the ends of the lining-strip; and screws 88, passing through the strap, the lining-material, and the edges of the felt 85, thread into the plate 78, to hold the parts together. A bead 89, formed upon the upper edge of the plate 78, has its edge directed rearward, to serve as a front support for 55 the cushion 80; and a plate 90, held by the screws 88, between the edges of the felt 85 and the strap 87, has its upper edge offset rearward, at 91, above the lining-member 79, to serve as a rear support for the cushion 80. The cushion 80 is, therefore, held, 60 throughout its length, against rearward and forward displacement, in a seat formed in the upper edge of the removable casing-member.

The upper edge of the casing-body, at 75 either side of the opening in the front wall thereof, is offset forward as shown at 92 in Figure 2; and the lower edge of the removable plate 78 is offset rearward at the same angle as the edge 92, so as to lie flatly 80 upon the latter. Studs 93 on the plate 78 (see Figures 2 and 5) are adapted to be registered with, and passed through, openings 94 in the offset front edge of the casing-body. For locking the plate 78 to the 85 casing-edge 92, there is, at each side thereof, a slide 95, held to the inner face of the edge piece 92 by headed pins 96, which pass through slots 97 in the slide. The plate 78, near each end thereof, carries a pin 98, adapted to be passed through an opening 99 in the edging piece 92, and to project beyond the inner face of the slide 95; and which terminates in a head 100. A shoulder 101 on the pin, together with the forward head of the pin, holds the same against forward and rearward displacement in the plate 78. The neck 102 of the pin, behind the plate 92, sets in a key-hole slot 100 alongside a wedge 103 on the slide 95. The opening 99 in the plate 92 is sufficiently large to permit the free passage therethrough of the inner head 100 of the screw in positioning the removable plate. At this time, the slide 95 will be at one side of the position thereof shown in Figure 5, so that the wedge 103 is out of the path of the head 100 of the pin as the plate 78 is set on the casing. The plate being in proper position on the casing, however, the slide is moved to its Figure 5 position, causing the wedge 103 to pass under the head 100 of the pin 98, thereby locking the plate 78 to the casing. The wedge not only locks the plate 78 to the casing, but draws the plate tightly 110 against the casing. The ends of the slots 97 by engagement with the pins 96 may determine the throw of the slide 95 in either direction. A finger-piece 105 is provided on the slide, whereby to operate the same. After the machine has been set in place, and while the casing-cover is still open, the removable piece 78 is set in place and the locking slides 95 operated by the handles 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 4 cushion 80, and, like the latter, may be held in a seat formed by a bead 107 on the lower front edge of the cover and by a plate 108 like the plate 90; the cushion and the plate 108 being held to the sheeting 11 of the cover by a strap 109 and screws 110.

In order that the work-sheets on the typewriter-carriage 111 may not catch upon the lining 13 of the rear of the cover, the cover is provided with an inner facing or lining of smooth sheet-material 112. The sheet 112, at its upper forward edge, is secured by screws 113 to a U-shaped portion 114 of a bar 115, which extends longitudinally of the cover at the rear of an opening or window 116 in the cover, through which the printing on the platen 117 may be observed. As shown in Figure 1, the bar 115 is continued down the sides of the opening 116; and, as shown in Figure 2, is continued along the front of the opening 116; serving as a frame or sash for a window-pane 118. The bar 115, along the several reaches thereof, is secured by rivets 119 to sheeting 11 of the cover. The pane, with its edges bound by a strip or strips of shock-absorbing material 120, is set within the U or channel shaped portions 114 of the bar, and against a peripheral flange or offset 121 thereof. The lining-piece 112 of the cover is extended slightly forward of its holding screws 113, as shown at 122 (Figure 2), to serve as a support for the rear edge of the window-pane. At its sides, the window-pane is held in its frame (see Figure 1), by metal strips 123, secured by screws 124 to the bar 115. At its front edge, the window-pane is supported by a rearward offset 125 of a bar 126, which may be one with the plate 108, forming part of the set for the upper cushion 106. The rear, side, and a portion of the front, reaches of the bar 115 have an upward offset or flange 127, which serves as a shade to intercept rays of light which would otherwise fall upon the glass at such angle as to be objectionably reflected into the eyes of the operator.

50 To serve as stops or rests for the cover, on the forward part of the casing-body, are two pieces of fiber 176, one at each side of the casing, secured to the casing by screws 177. The edge of the casing-cover 55 is recessed or cut away, at 178, to provide seats for the cover on the fiber-pieces 176; and these recesses are so shaped as to permit the cover to clear the fiber-pieces 176 when swung up and down around its hinge 60 12. The stops 176 and seats 178 positively determine the closed position of the cover, and eliminate the necessity for truing the opposing edges of the lining-strips at the sides of the cover and casing-body.

65 As to the removable member or plate 78,

it is to be noted that the construction and attachment thereof permit of the front of the casing, at the sides of the opening for the typewriter-keyboard, being continuous in one piece with the sheeting 10, forming the main body of the casing. Because of the character of the pieces 73, which extend along the side edges of the opening on the fixed front wall of the casing, such opening may be made of ample size to permit of easy insertion of the machine down through the casing-body to the base piece; without, however, causing open joints to be presented between the keyboard extension and casing front wall, and without necessitating any adjustment of parts to close the joints between the keyboard of the machine and the casing.

Variations may be resorted to within the scope of the invention, and portions of the improvements may be used without others.

Having thus described my invention, I claim:

1. A sound-deadening casing for a typewriting machine having a keyboard-extension, said casing having an opening in the front wall thereof through which said keyboard-extension may be passed, and a tubular resilient member fastened at each side of said opening for sealing the joints between said machine and said casing against the emission of sound.

2. A sound-deadening casing for a typewriting machine having a keyboard-extension, said casing having an opening in the front wall thereof through which said keyboard-extension may be passed, and means fastened at each side of said opening for sealing the joints between said machine and said casing against the emission of sound; said means including a flexible rubber tubing held in a folded strip of felt, one of said strips being fastened along each side of said opening with the tubing disposed adjacent the edges of the opening.

3. A sound-deadening casing for a typewriting machine, having an opening in the front wall thereof, through which the keyboard extension of the machine may be passed, and means at the edges of said opening, for sealing the joints between the casing and the machine, comprising resilient, tubular members adapted to be swung laterally, from normal position, by the keyboard extension, out of the path of the latter, and, by tendency to return to normal position, to bear against the keyboard extension.

4. The combination with a typewriting machine, of a sound-deadening casing having an opening in the front wall thereof for the keyboard extension of the machine, and means for sealing the joints between the casing and the machine at the sides of said opening, comprising tubular members flexibly mounted by strips of sound-deadening

- material, the lower portions of which members may be forced laterally farther apart by the keyboard extension, and the upper portions of which members may be forced 5 forward by contact with the front of the machine, both upper and lower portions being maintained more closely in engagement with the opposed machine-parts by the torsional tension of the members.
- 10 5. The combination with a typewriting machine having a keyboard-extension, of a sound-deadening casing including a metallic shell and a yieldable, felt, inner lining therefor, said casing having an opening in its 15 front wall for said extension to project therethrough, and means fastened along the sides of said opening for sealing the joints between said machine and said casing against the emission of sound, said means including 20 a rubber tube held in the folds of a flexible felt strip, the latter being fastened against the inner surface of said felt lining adjacent each side of said opening, said lining and said strips being disposed adjacent said opening, so that said tubes will be pressed against 25 said yieldable lining by the front of said machine when the latter is in place, thereby preventing said tubes from being pressed directly between metallic elements of said machine and said casing.
- 30 6. The combination with a typewriting machine, of a sound-deadening casing having a fixed front wall, cut away from the top thereof to provide passage for the keyboard extension of the machine in lowering the machine from the top of the casing to the base thereof, and flexible strips attached to the edges of the casing at the sides of the opening in the front plate thereof, to seal 35 the joints between the casing and the keyboard extension; said strips being laterally yieldable, to provide for the downward passage of the keyboard extension, and being flexible to bear closely against the keyboard 40 extension.
- 45 7. A sound-deadening casing for a typewriting machine, having a lower body-portion with a fixed front wall cut away from the top thereof to provide passage for the keyboard 50 extension of the machine in lowering the machine from the top of the body-portion to the base thereof, a plate adapted to be set on the front wall of the casing, above the keyboard extension of the machine, and manually operable means for detachably securing 55 such plate to the front wall of the body-portion at the sides of the opening in the latter.
- 60 8. A sound-deadening casing for a typewriting machine, having a lower body-portion with a fixed front wall cut away from the top thereof to provide passage for the keyboard extension of the machine in lowering the machine from the top of the body-portion to the base thereof, a plate extending 65 lengthwise of said casing and adapted to be set on the front wall of the body-portion, above the keyboard extension of the machine, and means for securing such plate to the front wall of the body-portion at the 70 sides of the opening in the latter; said attachable plate having a seat thereon for a cushion adapted to form one wall of a slot through and along which the operating levers of the carriage of the machine may 75 pass.
9. A sound-deadening casing for a typewriting machine, having a lower body-portion with a fixed front wall cut away from the top thereof to provide passage for the 80 keyboard extension of the machine in lowering the machine from the top of the body-portion to the base thereof, a plate adapted to be set on the front wall of the body-portion, above the keyboard extension of the 85 machine, and means for securing such plate to the front wall of the body-portion at the sides of the opening in the latter; said attachable plate having fixed thereto, where it crosses the opening in the wall of the 90 body-portion, a pendant strip of sound-deadening material.
10. A sound-deadening casing for a typewriting machine, having a lower body-portion with a fixed front wall cut away from 95 the top thereof to provide passage for the keyboard extension of the machine in lowering the machine from the top of the body-portion to the base thereof, a plate adapted 100 to be set on the front wall of the body-portion, above the keyboard extension of the machine, and means for securing such plate to the front wall of the body-portion at the sides of the opening in the latter; said means comprising registerable pin-and-socket connections on the plate and said front wall, a slotted slide on the said front wall, and a pin on the plate projecting through said front wall, and having a head on its inner 105 end to be engaged by the slide when the latter is moved to locking position.
11. A sound-deadening casing for a typewriting machine including a lower body-portion with a fixed front wall, the latter having a section cut away from the top 110 thereof downwardly to provide for lowering the keyboard-extension of said machine, a plate extending lengthwise of said casing and arranged against the inner side of said front wall, and means for detachably securing 115 said plate to said wall, said means including a slide shiftable laterally on the inner face of said plate on each side of the opening in said wall, and pins arranged to be held in said wall and for passing through 120 said plate into the path of said slides, the latter being arranged with cam-portions for engaging under head-portions provided on the inner ends of said pins, each of said 125 slides being further arranged with a handle 120

at its outer end, whereby the slides may be readily actuated manually for fastening or unfastening said plate.

12. A sound-deadening casing for a typewriting machine, having a lower body-portion with a fixed front wall, cut away from the top thereof to provide passage for the keyboard extension of the machine in lowering the machine from the top of the body-portion to the base thereof, a plate adapted to be set on the front wall of the body-portion, above the keyboard extension of the machine, and means for securing such plate to said front wall at the sides of the opening in the latter; said means comprising a slide horizontally shiftable on the inner face of the front of the body-portion at each side of the opening therein, pins held in said wall and passing through said plate adapted to be passed through said front wall into the path of movement of the slides, and cam-positions on the slides for engaging the pins and camming the plate tightly to said front wall when the slides are moved to plate-locking position.

13. A sound-deadening casing for a typewriting machine, including a sheet-metal body, sheets of felt or other sound-deadening material lining said body interiorly, bushings staked or riveted into the sheeting of the casing, and passing therefrom through the lining-material, straps set on the ends of bushings against the lining-material, and screws or pins passing through the straps and into the bushings, to hold the straps and lining-material fast to the metal-sheeting.

14. A sound-deadening casing for a typewriting machine, having an opening in the top thereof, through which the printing on the platen may be observed, a pane of transparent material, set to the opening, against the under side of said top, and a rail fixed to the casing marginally of said pane and having a portion protruding upward through said opening to shade the pane from light-rays which would be reflected by the pane to the operator.

15. A sheet-metal sound-deadening casing for a typewriting machine, having an opening through which the printing on the platen may be observed, a pane of transparent material, set interiorly to the opening, a lining of sound-deadening material, a facing of smooth sheet-material for the rear upper part of the casing, a rail set marginally of the opening, and protruding upward from the casing to shade the pane from light-rays which would be reflected to the operator; said rail having a flange set against the inner face of the casing sheet-material, for securing the rail to the casing, and to

serve as a seat for the pane, and an L-shaped offset from the flange to serve as a frame for the pane, and as a seat for the smooth inner lining-piece.

16. A sheet-metal sound-deadening casing for a typewriting machine, having an opening through which the printing on the platen may be observed, a pane of transparent material set to the opening, a lining of sound-deadening material, a facing of smooth sheet-material for the rear upper part of the casing, a rail set marginally of the opening, and protruding upward from the casing to shade the pane from light-rays coming from the rear and sides which would be reflected to the operator; said rail having a flange set against the inner face of the casing sheet-material, for securing the rail to the casing, and to serve as a seat for the pane, and an L-shaped offset from the flange to serve as a frame for the pane, and as a seat for the smooth inner lining-piece; which lining-piece is secured to such seat, and is extended forward thereof to overlap and hold the pane in place.

17. A sound-deadening casing for a typewriting machine having a keyboard-extension, said casing having a lower body-portion shell of sheet-metal, and a top shell of sheet-metal, arranged with a reinforcing bead adjacent its lower extremity, said bead-portion being integrally formed on said top shell in the back and side walls thereof, said top shell and said lower body-portion shell each having a portion cut away at the front for forming a lengthwise actuating slot, said body-portion shell also having a section of its front wall cut away to permit said keyboard-extension to pass therethrough and a plate fastened to the front wall of the lower body-portion over the keyboard-opening and extending upwardly so as to partly close said slot-opening, said plate having a bead-portion arranged to form a continuation of the bead on said top shell for increasing the strength and appearance of said casing.

18. The combination with a typewriting machine having a closed front, of a sound-deadening casing comprising a front wall having an opening therein through which a portion of the machine extends, tubular flexible members for sealing the joints between the frame of the machine and the casing at the sides of the opening, a bottom plate for said casing, and cups on said bottom plate to receive the feet of the machine, said cups being effective to hold the machine against the slot-sealing members.

ALFRED G. F. KUROWSKI.
